DAVENPORT

Joseph Goulart, San Diego, Calif.

Application April 27, 1951, Serial No. 14,991

Term of patent 3½ years

(Cl. D15—11)

To all whom it may concern:

Be it known that I, Joseph Goulart, a citizen of the United States of America, residing at San Diego, in the county of San Diego and State of California, have invented a new, original, and ornamental Design for a Davenport, of which the following is a specification, reference being had to the accompanying drawing, forming a part thereof.

The figure of the drawing is a perspective view of a davenport showing my new design. The opposite end is similar to that shown and the back is plain.

I claim:

The ornamental design for a davenport, substantially as shown and described.

JOSEPH GOURLART.
